UNITED STATES PATENT OFFICE.

THOMAS CORSCADEN, OF NEW BRITAIN, CONNECTICUT, ASSIGNOR TO THE AMERICAN PULLEY COMPANY, OF PHILADELPHIA, PENNSYLVANIA.

DESIGN FOR A PULLEY.

SPECIFICATION forming part of Design No. 29,543, dated October 25, 1898.

Application filed May 8, 1897. Serial No. 635,745. Term of patent 14 years.

To all whom it may concern:

Be it known that I, THOMAS CORSCADEN, a citizen of the United States, residing at New Britain, in the county of Hartford and State 5 of Connecticut, have invented and produced a new and original Design for a Pulley, of which the following is a specification, reference being had to the accompanying drawing, in which the figure is a perspective view of a 10 pulley, showing my design.

The leading or material feature of my design consists of a pulley, substantially as shown.

A designates the rim, which is circular in 15 side view. Its face is nearly flat, and each edge is in the form of an internal roll or bead 2 of circular form in cross-section. At the middle portion of said rim is an inwardly-projecting and central rim-flange 3 with flat sides 20 and a square edge. On diametrically opposite sides, inside of the rim, are the rim-bolt clamps 4 of the contour shown. The spoke-

arms 5, of which there are six pair, have straight edges and a rounded central longitudinal corrugation or bead 6, which begins near 25 the rim and extends to the hub. The said arms extend inwardly from the rim in a radial direction to the hub 7 and are arranged in pairs, the two members thereof coming nearer together at the rim 5 and then diverging 30 or spreading gradually from each other as they approach the hub. At each end of the hub are the clamps 8 of the contour shown, the same giving the pulley, as seen in side view, the appearance of having a rectangular 35 hub.

What I claim as new, and desire to secure by Letters Patent, is—

The design for a pulley, as herein shown and described.

THOMAS CORSCADEN.
